CLAIM

The ornamental design for a seat and back support for
collapsible chair, as shown and described.

DESCRIPTION

FIG. 1 is a perspective view showing my new design.

FIG. 2 is a front view thereof.

FIG. 3 is a rear view thereof.

FIG. 4 is a left side view thereof.

FIG. 5 is a right side view thereof.

FIG. 6 is a top view thereof showing the seat and back
support for collapsible chair of my new design displaced in
flat-laid condition; and,

FIG. 7 is a bottom view thereof showing the seat and back
support for collapsible chair of my new design displaced in
flat-laid condition.
